DOOR HANDLE

Leo J. Maffei, New Britain, Conn., assignor to Emhart Corporation, Bloomfield, Conn., a corporation of Connecticut

Filed Apr. 30, 1965, Ser. No. 85,036

Term of patent 14 years

(Cl. D50—3)

FIG. 1

FIG. 3

FIG. 1 is a front elevational view illustrating the door handle embodying my new design.

FIG. 2 is a side elevational view of said door handle, the opposite side being a mirror image of that shown.

FIG. 3 is a rear elevational view of said door handle.

The top and bottom surfaces are flush with the top and bottom edges, respectively.

I claim:

The ornamental design for a door handle, substantially as shown and described.
